Attorney

UNITED STATES PATENT OFFICE.

SAMUEL SHAFFER, OF HIAWATHA, KANSAS.

SHIELD FOR RAILWAY CARS.

Application filed November 12, 1923. Serial No. 674,262.

To all whom it may concern:

Be it known that I, SAMUEL SHAFFER, a citizen of the United States of America, and resident of Hiawatha, in the county of Brown and State of Kansas, have invented certain new and useful Improvements in Shields for Railway Cars, of which the following is a specification.

This invention relates to shields or forts for use in cars, and the said invention relates particularly to a bullet-proof shield or case in which refuge may be taken by railway employees, express messengers, mail clerks and the like in order that they will be protected from the fire of bandits or robbers.

It is an object of this invention to produce a case of the character indicated from which the occupants may observe the movement of the robbers and from which they can direct a fire to protect themselves and the contents of the car.

It is a further object of this invention to produce a case of the character indicated in which port holes, through which firing is to be done, may be guarded by movable plates, so that the port holes may be covered or uncovered, as the defense progresses.

It is a further object of this invention to produce a case having means for ventilation and for seeing the interior of the car in any direction in which the case is placed.

It is a still further object of this invention to produce a case of the character indicated which will be comparatively inexpensive to manufacture and which will prove safe from bullet fire or attack intended to demolish the case.

With the foregoing and other objects in view, the invention consists in the details of construction, and in the arrangement and combination of parts to be hereinafter more fully set forth and claimed.

In describing the invention in detail, reference will be had to the accompanying drawings forming part of this application wherein like characters denote corresponding parts in the several views, and in which—

Figure 1 illustrates a view in elevation of a fort embodying the invention;

Figure 2 illustrates an enlarged detail

view of a fragment of the interior of the fort;

Figure 3 illustrates a sectional view on the 55 line 3—3 of Fig. 2; and

Figure 4 illustrates a sectional view of the bottom of the fort and its anchorage.

In these drawings it is shown that the fort comprises a shell 5 which is preferably 60 cylindrical and provided with inwardly turned apertured lugs 6 at the base, which lugs are secured to the floor 7 of a car by fastenings 8 such as bolts. Any number of lugs and fastenings may be provided, according to the requirements in practice, to produce proper anchorage for the fort. The case has an opening that is guarded by a door 9 secured on hinges 10 in order that the door will close, and the said door has a 70 latch 11 on its inner side that will engage a fastener 12 of any well known construction. As the particular form of latch and retaining device may be varied to suit particular requirements, these features are, but conveniently shown.

The upper end of the fort has a horizontally disposed flange 13 to which a top plate or cover 14 is secured by fastenings 15 such as bolts, the top plate, of course, being 80 preferably made of metal which is bullet-proof.

A series of port holes 16 are formed in the shell and in the door, and these port holes are each provided with a door or 85 shield 17 that moves horizontally in the guides 18 and 19 secured to the inner surface of the shell. The guides are flanged as shown and the guards slide between the flange and the inner surface of the shell, and if desired, means may be provided for holding the guards at different positions of adjustment, either to close the port hole or to guard it. The guides are secured in place by fastenings 20 such as screws that may 90 extend through the guides and be anchored in the shell. The shell is further provided with a plurality of peep holes 21, through which the movements of the robbers may be observed and by which the defensive fire 100 may be more accurately directed.

The refuge of this application has been described as of utility in cars, but it will be understood and it is also stated that it is

likewise intended for banking houses and trust companies and business houses or any place where money or valuable property is kept, and the invention in discussion is to protect this property and protect life as well.

I claim:

In a fort of the character described, a cylindrical shell having lugs extending inwardly from the lower edge adapted to receive means for securing the lugs to a car floor, the said shell having a series of port holes positioned in alinement around the

shell and sight openings thereabove, a guide secured to the inner surface of the shell below the port holes and having an upwardly extending flange, a guide secured to the inner surface of the shell above the port holes and having a downwardly extending flange adapted to coact with the first mentioned guide and flange, curved guards slidably between the guides and held in position by the flanges to close the port holes, and a door for the said shell having means interiorly of the shell for holding the door closed.

SAMUEL SHAFFER.
